F. D. FARR

HANDLE

Filed Feb. 9, 1922

INVENTOR.
FRED D. FARR

BY *Frank Keipos*
ATTORNEYS.

UNITED STATES PATENT OFFICE.

FRED D. FARR, OF PERRY, NEW YORK.

HANDLE.

Application filed February 9, 1922. Serial No. 535,389.

To all whom it may concern:

Be it known that I, FRED D. FARR, a citizen of the United States, residing at Perry, in the county of Wyoming and State of New York, have invented certain new and useful Improvements in Handles, of which the following is a specification.

The object of this invention is to provide a new and improved type of handle which 10 can be slipped over the end of the fuel feed and ignition control levers of a Ford automobile for the purpose of providing means whereby the levers can be operated with more ease while holding on the steering 15 wheel.

These and other objects of this invention will be fully illustrated in the drawing, described in the specification and pointed out in the claims at the end thereof.

20 In the accompanying drawing:

Figure 1 is a perspective view of a steering wheel with the improved handles attached to the control levers thereof.

Figure 2 is a perspective view of the end 25 of one of the control levers before the improved handle is attached thereto.

Figure 3 is a perspective view of the same handle after one of the improved handles has been attached thereto.

30 Figure 4 is a vertical longitudinal section of the end of the control lever and the handle attached to it, taken on the line 4^x—4^x of Figure 3.

Figure 5 is a vertical cross section of the 35 control lever and handle thereon, the section being taken on the line 5^x—5^x of Figure 4.

Figure 6 is a vertical cross section of the control lever the section being taken on the line 6^x—6^x of Figure 4.

40 Figure 7 is a front elevation of one of the improved handles provided on the end of the control levers.

Figure 8 is a perspective view of an improved type of the handle.

45 In the several figures of the drawing like reference numerals indicate like parts.

The control levers by means of which the gasoline feed and ignition of a Ford automobile are regulated are located below the 50 steering wheel and project radially from the steering post. With the handles that are now formed integral on the end of each of these levers as illustrated in Figure 2, it is difficult to reach these levers with the fingers,

take hold of them and operate them while 55 keeping the hands on the rim of the steering wheel.

The handle forming the subject matter of this invention is intended to remedy this trouble and allow the driver of the car to 60 operate each of the levers while holding on the steering wheel. As will be seen from an inspection of Figure 2 the handle for the lever as it comes from the manufacturer 65 comprises nothing more than a flattened portion at the end of the five-sixteenth rod which forms the remainder of the lever. This handle does not permit the operation of the lever in an efficient and convenient manner as the fingers cannot very well take hold 70 of it or keep in touch with it without taking the whole hand off the steering wheel. The handle which is to remedy this trouble comprises the rubber ball 1 having the sleeve 2 provided on one side thereof and integral 75 therewith.

The hole through the sleeve 2 is made large enough to allow the shank 3^a of the control lever to be gripped by the sleeve after it has been slipped over it. The inside 80 of the rubber ball is made hollow to receive the flattened end of the control lever. The hollow inside of the ball 1 comprises an enlarged pocket of the shape of the flattened end of the control lever which is intended to 85 be placed therein. The hole of the sleeve 2 leads into this pocket and in placing the handle formed by the rubber ball and sleeve the flattened end of the control lever is forced first through the round hole in the sleeve 90 which it distorts until the flattened end of the control lever has passed through the sleeve and is embedded into the pocket in the ball proper when the hole in the sleeve 95 will return to its original shape and encircle the shank of the lever.

The handle is thus rigidly held in place on the end of the control lever to slightly extend the control lever while forming a suitable handle thereon which can be readily 100 taken hold of and operated by the driver of the car. To further facilitate the ready engagement of the fingers with the handle for the purpose heretofore pointed out, the rubber ball 1 is provided with a pair of depressions 3 and 4 in the front thereof. These depressions are located on the rubber ball 105 so that the tips of two of the fingers of the

driver can readily be laid into these depressions in order to allow the driver to use either one or the other of these fingers to push the control lever in the desired direction. The depressions 3 and 4 conform to the outline of the finger tips to allow them to turn therein in the manner of a ball and socket joint. A contact of the finger tips with the handle is thus made possible at 10 different angles which helps in the operation of the control levers.

The flattened end of the control lever and its engagement with the correspondingly shaped pocket on the inside of the ball portion of the handle operates to hold the handle and its depressions in the same predetermined position at all times so that the finger tip can engage with the depressions and take hold of the handle in the manner 20 above described. To make the surface of the ball a still better object to grip with the fingers a series of concentric ridges 5 are formed thereon.

In Figure 8 is shown a modified form of 25 the handle. This handle is formed of but half of a rubber ball and without a sleeve provided on one side thereof. A longitudinal pocket is provided in the center of the rear of the ball to receive the flattened end 30 of the control levers in the same manner in which these ends engage into the pocket formed in the preferred type of handle illustrated in Figure 3.

While the handles above described are 35 preferably made of soft rubber which provides for the fingers a better grip due to the resilient contact they make with the handle, other material may be used instead especial-

ly for the form of handle illustrated in Figure 8.

40

I claim:

1. An extension handle for fuel and ignition control levers comprising a ball member having a pocket formed therein, a sleeve having its duct leading into the pocket formed on one side of said ball member, the duct in said sleeve being of smaller dimension than the pocket in said ball member, said sleeve being adapted to expand and slip over a handle and then contract in back 50 of the handle to lock the handle in place in the pocket in said ball member, means provided in the surface of said ball members to receive the finger tips of the hand operator to permit a movement of the ball member with the handle to which it is attached by the finger tips.

2. An extension handle for fuel and ignition control levers comprising an elastic ball member having a flat pocket formed therein, 60 a pair of depressions formed on the outside of the ball in a definite relation to the flat pocket within, said depressions being adapted to receive the tips of two fingers by which it may be pushed directly in either direction.

3. An extension handle for fuel and ignition control levers comprising an elastic ball member having a flat pocket formed therein, a depression formed on the outside of the ball in a definite relation to the flat pocket 70 within, said depression being adapted to receive the tip of a finger by which it may be pushed directly in one direction.

In testimony whereof I affix my signature.

FRED D. FARR.
